UNITED STATES PATENT OFFICE.

JOSEPH E. FORSYTH, OF CHICAGO, ILLINOIS.

TRAIN-PIPE COUPLING.

1,381,865.

Specification of Letters Patent. Patented June 14, 1921.

Application filed June 21, 1920. Serial No. 390,574.

To all whom it may concern:

Be it known that I, JOSEPH E. FORSYTH, a citizen of the United States, residing at Chicago, in the county of Cook and State of Illinois, have invented a new and useful Improvement in Train-Pipe Couplings, of which the following is a specification.

This invention relates particularly to automatic train-pipe couplings of the general character set forth in Letters Patent of the United States No. 848,840, granted March 12, 1907, to Joseph E. Forsyth.

For passenger service, it is usual to employ a coupling head which is supported from the draw-bar of the car in the manner illustrated, for example, in Forsyth United States Patent No. 846,841, granted March 12, 1907; and it is usual to connect the signal-pipe, the brake-pipe, and the steam-pipe of the car with corresponding passages or conduits with which the coupling head is provided, said conduits being equipped at their orifices with suitable gaskets.

The primary object of the present invention is to provide means, whereby the brake-pipe, for example, of one car, may be placed in communication with the signal-pipe, for example, of another car, so that the signal-pipe may be utilized for conducting air-pressure for braking purposes to the cars in the rear of a disabled car. It may be explained that it sometimes happens that the brake-pipe, or the connections of the brake-pipe of a car, become injured; and the present invention contemplates the employment, at each end of such a car, of a plate adapted to be interposed between the train-pipe coupling heads at each end of such a car, such plate being provided with means for closing the brake-pipe at each end of the defective car and connecting the brake-pipes of the adjoining cars with the signal-pipe of the car which carries the defective brake-pipe, thus shunting the air for braking purposes through the signal-pipe. In this manner, the effective operation of the brakes can be maintained upon all of the cars of the train, except the car which has the defective brake-pipe.

The invention is illustrated, in its preferred embodiment, in the accompanying drawing, in which—

Figure 1 represents a vertical sectional view of a pair of train-pipe coupling heads of an automatic train-pipe coupling and an

interposed plate provided with means for shunting air-pressure from a given pipe (the brake-pipe) of one car to another pipe (the signal-pipe) of another car; Fig. 2, an elevational view of the shunting-plate employed; and Fig. 3, a vertical sectional view taken as indicated at line 3 of Fig. 2.

In the drawing, A represents a train-pipe coupling head of a car in which the brake-pipe (the central pipe) is assumed to be defective; B represents a train-pipe coupling head of an adjoining car; and C represents a shunting plate employed. The coupling head A is provided with a pair of guide prongs A' (one shown); and the coupling head B is provided with a pair of guide prongs B' (one shown). The guide prongs of the two coupling heads are adapted to interlock in the usual manner to prevent rotation of the coupling heads with relation to each other. The coupling heads are supported by stems 1 and backed by springs 2, in a well-known manner. Each coupling head is provided with a signal passage 3, a brake passage 4 and a steam passage 5. With these passages communicate the train pipes, that is, the signal-pipe 3^a, the brake pipe 4^a, and the steam pipe 5^a. At the orifices of the passages are provided the usual gaskets 3^b, 4^b and 5^b.

The shunting plate C comprises a flat plate of the same contour as the faces of the coupling heads, and thus adapted to be embraced by the guide prongs of the coupling heads when the coupling heads come together. The plate C is provided with a passage or conduit 6 which has a central orifice 6^a at one side of the plate, and an eccentric orifice 6^b at the other side of the plate. Opposite the orifice 6^a, the plate is provided with a central projection, or boss, 7 which is adapted to fit into the central gasket 4^b of the corresponding coupling head; and opposite the orifice 6^b, the plate is provided with a boss, or plug, 7^a which is adapted to fit into the gasket 3^b of the other coupling head. Thus, it will be seen that by this means the brake-pipe of one car is stopped up, while the signal-pipe of the other car is stopped up; and that the signal-pipe of one car is placed in communication with the brake-pipe of the other car.

This arrangement enables the air to be shunted from the brake-pipe of one car to the signal-pipe of the other car in the manner indicated by the arrow. At the opposite

end of the car having the defective brake-pipe, another shunting plate of the same kind is employed, but turned side for side, so that at that point the air will be shunted back from the signal-pipe of the car having the defective brake-pipe to the brake-pipe of the adjoining car, while the signal-pipe of such adjoining car will be stopped up. In this manner, the air can be shunted through the signal-pipe of the car having the defective brake-pipe; and thus, it will be possible to effectively control the train until such time as it is feasible to set the car out for repairs. The continuity of the signal-pipe, for signal purposes, will, of course, be interrupted; but the signals can be operated from any car in front of the car having the defective brake-pipe.

It may be stated, that once the coupling heads are together with the shunting plate interposed, the plugs 7 and 7^a of the plate are no longer really needed to close the train-pipes which are, for the time being, thrown out of use, as this might be accomplished by the gaskets pressing against the sides of the plate. However, it is preferred to employ the plugs on the plate, as this affords a ready means of attaching the plate to one of the coupling heads preparatory to bringing the cars together. That is, when one of the plugs is inserted in a gasket, the plate will be frictionally held in position and will not drop off during the coupling of the cars. Rotation of the plate about the axis of the plug will not occur, for the reason that the edges of the plate conform to the concave surfaces of the base portions of the guide prongs or horns of the coupling head.

40 The foregoing detailed description has been given for clearness of understanding only, and no unnecessary limitation should be understood therefrom, but the appended claims should be construed as broadly as permissible in view of the art.

What I regard as new, and desire to secure by Letters Patent, is—

1. The combination with a pair of train-pipe coupling heads provided with a plurality of passages adapted to register in pairs, of an interposed plate provided with a conduit through which a passage of one coupling head communicates with a non-registering passage of the other coupling head.

2. The combination with a pair of train-pipe coupling heads provided with a plurality of passages having gasket-equipped orifices, of an interposed plate having a shunting passage provided at opposite sides of the plate with orifices which register with said first-named orifices and thus serve to

connect a given train-pipe of one car with another kind of train-pipe of another car.

3. The combination with a pair of train-pipe coupling heads provided with guide-prongs and with a plurality of passages having gasket-equipped orifices, of an interposed plate having a shunting passage provided at opposite sides of the plate with orifices which register with the gasket-equipped orifices in such manner as to shunt the pressure from a given train-pipe of one car to a different train-pipe of another car, said plate being equipped with a boss adapted to engage one of the coupling-head gaskets to retain the plate in position during the coupling of the cars.

4. In means of the character set forth, the combination of a pair of coupling heads provided with guide prongs and with signal passages and brake passages having orifices equipped with gaskets, and an interposed shunting plate provided with a shunting conduit and provided on opposite sides with plug portions, one of which is adapted to close the orifice of a signal-pipe and the other of which is adapted to close the orifice of a brake pipe.

5. In means of the character set forth, the combination of a coupling head provided with guide prongs and equipped with passages for communication with corresponding train-pipes, said passages having orifices equipped with gaskets, and a shunting plate having its edge portions embraced by the base portions of said guide prongs, said shunting plate being provided with a shunting conduit having orifices in alignment with the passages of said gaskets and having a plug opposite one of the orifices of the plate adapted to enter a gasket.

6. A device of the character and for the purpose set forth, comprising a plate provided with a shunting passage having orifices at opposite sides of the plate which are out of alignment with each other, said plate having an edge portion adapted to be embraced by the guide prongs of a coupling head.

7. A device of the character and for the purpose set forth, comprising a plate provided with a shunting passage having orifices at opposite sides of the plate which are out of alignment with each other, said plate having an edge portion adapted to be embraced by the guide prongs of a coupling head and having a projection adapted to enter a gasket of a coupling head and support the plate during the coupling operation.

JOSEPH E. FORSYTH.
